UNITED STATES PATENT OFFICE.

EDGAR E. FOSTER, OF MONTGOMERY, ALABAMA.

BOXING APPARATUS.

Application filed April 28, 1926. Serial No. 105,290.

My invention relates generally to improvements in boxing apparatus for use in a gymnasium, the home or other suitable place for recreation and for the physical 5 development of the user, and it consists in the combinations, constructions and arrangements herein described and claimed.

An object of the invention is the provision of a "dummy" boxer or punching device 10 which normally will remain in upright position and which will automatically swing back to upright position quickly after having been knocked from normal position by a blow.

15 A further object of the invention is the provision of a device of the character described which affords facilities for supporting a padded punching head or impact receiving member yieldingly in a desirable 20 position so that it can be struck conveniently and forcibly by the hands of a user of the device and will yield under the impact of a blow but will be returned automatically to its original position.

25 A still further object of the invention is the provision of a device of the character described which is simple in construction, not likely to get out of order, and thoroughly practical for the purpose for which 30 it is intended.

Other objects and advantages of the invention will be apparent from the following description, considered in conjunction with the accompanying drawings, in which

35 Figure 1 is a perspective view of the improved punching device.

Figure 2 is a vertical central section through the device.

The improved punching device comprises 40 a base 1 which may be hemispherical as shown and is made of heavy hardwood or any other suitable material. The base 1 rests on the convexly curved surface 2 thereof so that the top surface 3 thereof normally 45 will lie in a horizontal plane, the base normally being maintained in this position by reason of the provision of a weight, such as the mass of lead or other relatively heavy substance indicated at 4 which fills an axial 50 socket 5 that is formed in the base 3 to open through the top face 3 of the base centrally of the latter. The base thus may rock on a flat supporting surface, such as indicated at 6, but will automatically return to the 55 position shown in Figures 1 and 2.

The device also includes an upright sup-

porting member 7 which is shown as being a hollow body that may be polygonal in cross sectional configuration. The upright hollow body 7 may decrease in cross sectional area from its lower end for the greater part of its height, the extreme upper end portion of the hollow body being uniform in cross sectional area as indicated at 8. The upright walls of the body 7 may be stayed to each other and the body 7 thus strengthened by horizontal plates such as indicated at 9, 10, 11 and 12. These plates fit snugly in the body 7 at different levels, the plate 9 being shown as fitting in the 70 lower end portion of the body 7 so that the lower face of the plate 9 is flush with the lower edges of the walls of the body while the plates 11 and 12 are disposed at the lower end and the upper end, respectively, of the upper end or head portion 8 of the body and the plate 10 is disposed within the body between the plates 9 and 11 and somewhat nearer to the plate 11 than to the plate 9. These reinforcing plates 80 may be secured to the walls of the body in any suitable known manner, as for example by the fastening devices indicated at 13 for the plate 9 and at 14 for the plate 10.

In assembling the body and the base of the device, the lower plate 9 may first be placed on the flat upper face 3 of the base centrally of the latter and secured firmly to the base in any suitable known manner, as by means of the fastening screws 15. The body 7 then is placed on the base with the lower end portion thereof fitting on the plate 9 and the body 7 thus will be disposed in alignment with the vertical axis of the base 1 and will be connected with the base 90 to move with the latter as a unit when the lower end portion of the body 7 is secured to the plate 9 by means of the aforesaid fastening devices 13.

The upper end or head portion 8 of the 100 body is padded externally by a layer 16 of cotton or other suitable relatively soft or yielding material. The layer of padding is of sufficient thickness to prevent injury to the hand of a user of the device who makes use of the device by striking with his clenched hands the padded upper end or head portion of the body of the device. The layer of padding preferably is disposed flatwise against the lateral faces of the 105 upper end portion 8 of the body 7 so that the padded head portion of the device will 110

have a plurality of lateral faces, any one of which may be struck by the user of the device.

From the foregoing description of the various parts of the device, the operation thereof will be readily understood. The weighted base will be self-righting so that the supporting body 7 normally will remain in vertical position. The padded 10 upper end portion of the body of the device is termed the punching head or impact receiving member and the impact of a blow against any one of the lateral faces of this punching head will cause the device to rock 15 on its base in the direction in which the force of the blow is exerted. As soon as the force of the blow is dissipated, the device will swing back by gravity to normal position, the body then being again vertically disposed. The combined height of the base 1 and the body 7 is such that the punching head will be disposed at a desirable height above the floor 6 with respect to the height of the user of the device. The user 25 of the device then may strike the punching head with his fist or alternately with each fist and the device will be actuated under the impact of each blow on the punching head so that the punching head will swing 30 away from the user of the device but will be returned automatically to position to be struck again by the user of the device. Thus the punching head always will swing away from the user after each blow and then back 35 to the position to be struck again before such further blow can be struck.

The resistance that will be opposed by the device to the blows of the user of the device of course will vary with the size 40 and weight of the base of the device but preferably will be sufficient to require an impact of considerable force to cause any appreciable swinging movement of the punching head portion of the device. This 45 will permit the user of the device to strike the punching head with relatively great force without tending to lose his balance each time a blow is struck.

The device is adapted especially for use 50 in a gymnasium or in a home both to afford recreation to a user and to improve his physical condition and health. It is obvious that the members of the device may vary considerably in details of construction from 55 those which are illustrated in the drawings

and I therefore consider as my own all such modifications and adaptations thereof as fairly fall within the scope of the appended claims.

I claim:—

1. A boxing device comprising a base having a convexly curved lower face and a substantially flat upper face, said base having a vertical socket opening through said upper face centrally of the latter, a relatively 65 heavy substance disposed in said socket, a hollow supporting body secured at its lower end to said base so that the axis of said supporting body coincides substantially with the vertical axis of said base, and a 70 punching head carried at the upper end of said supporting body, said hollow body tapering in cross sectional area from its lower end to said punching head.

2. A boxing device comprising a base having a convexly curved lower face and a substantially flat upper face, a weight imbedded in said base along the vertical axis of the base, a hollow body upstanding on said base with the axis of said hollow body 80 substantially aligned with the vertical axis of the base, horizontal reinforcing plates in said hollow body, one of said horizontal plates being disposed at the lower end of said body and serving as a connector between the lower end portion of the body and said base, and a layer of padding on the upper end portion of said hollow body, whereby the padded upper end portion of said hollow body constitutes a punching 85 head.

3. A boxing device comprising a base having a convexly curved lower face and a substantially flat upper face, a weight imbedded in said base along the vertical axis of the 95 base, a hollow body upstanding on said base with the axis of said hollow body substantially aligned with the vertical axis of the base, horizontal reinforcing plates in said hollow body, one of said horizontal plates 100 being disposed at the lower end of said body and serving as a connector between the lower end portion of the body and said base, and a layer of padding on the upper end portion of said hollow body, whereby the padded upper end portion of said hollow body constitutes a punching head, said punching head being polygonal in cross sectional configuration.

EDGAR E. FOSTER.
